UNITED STATES PATENT OFFICE.

ERNST THOMA, OF MAYWOOD, NEW JERSEY.

DESIGN FOR JEWELRY.

SPECIFICATION forming part of Design No. 13,402, dated November 7, 1882.

Application filed October 3, 1882. Term of patent 7 years.

To all whom it may concern:

Be it known that I, ERNST THOMA, a citizen of the United States, residing at Maywood, in the county of Bergen and State of New Jersey, 5 have invented and produced a new and original Design for Jewelry, of which the following is a specification, reference being had to the accompanying drawing.

This design consists in a scroll-shaped ring 10 resembling the letter O and the image of a deer in the act of jumping through said ring.

The drawing represents a face view of my design.

In this drawing the letter A designates a 15 scroll-shaped ring resembling the letter O, and the letter B designates the image of a deer in the act of jumping through said scroll-shaped ring.

In the example represented by the drawing

I have shown my design as applied to a lace-pin; but it is obvious that said design can be applied to various articles of jewelry, such as ear-rings, sleeve-buttons, finger-rings, bracelets, &c.

What I claim as new, and desire to secure 25 by Letters Patent, is—

The design for jewelry, consisting of a scroll-shaped ring resembling the letter O, and the image of a deer in the act of jumping through said ring, as shown and described. 30

In testimony whereof I have hereunto set my hand and seal in the presence of two subscribing witnesses.

ERNST THOMA. [L. S.]
